UNITED STATES PATENT OFFICE.

SAMUEL R. KELLY, OF ALLEGHENY, PENNSYLVANIA.

DESIGN FOR A BOTTLE.

SPECIFICATION forming part of Design No. 32,471, dated April 10, 1900.

Application filed March 15, 1900. Serial No. 8,847. Term of patent 14 years.

To all whom it may concern:

Be it known that I, SAMUEL R. KELLY, a citizen of the United States, residing at Allegheny, in the county of Allegheny and State of Pennsylvania, have invented and produced a new and useful Design for Bottles, of which the following is a specification.

My invention relates to new and original designs in bottles.

10 In the accompanying drawings, Figure 1 is a front elevation of my invention. Fig. 2 is a rear elevation of the same. Fig. 3 is an edge view. Fig. 4 is a horizontal section on the line α α , Fig. 1.

15 As shown in the drawings, the leading feature of my design consists of a bottle having a convex face or front, a paneled rear surface or back, and a plain neck and arched shoulders.

20 The upper edge of the convex face of the bottle is curved and the rear surface at the shoulder of the bottle is arched or curved. The panel upon the rear surface is depressed,

and the border of said panel is a plain bevel, the upper portion of which is arched to conform to the shape of the shoulder of the bottle. 25

The side edges of the bottle are each provided with a panel depressed and bordered like the rear surface, but having a plain upper surface. 30

The neck of the bottle is plain, and surrounding the mouth at the top edge is a bead with a ring below it.

Having thus described my invention, what I claim is— 35

The design for a bottle, substantially as shown and described.

In testimony whereof I have hereunto set my hand in presence of two subscribing witnesses. 40

SAMUEL R. KELLY.
